UNITED STATES PATENT OFFICE.

THOMAS CARNEY, OF CHICAGO, ILLINOIS, ASSIGNOR TO MOSES BENSINGER,
OF SAME PLACE.

CASH-REGISTER.

SPECIFICATION forming part of Letters Patent No. 428,270, dated May 20, 1890.

Application filed February 8, 1890. Serial No. 339,748. (No model.)

To all whom it may concern:

Be it known that I, THOMAS CARNEY, residing at Chicago, in the county of Cook and State of Illinois, and a citizen of the United States, have invented a new and useful Im-

provement in Cash-Registers, of which the following is a specification, reference being had to the accompanying drawings, in which—

Figure 1 is a plan. Fig. 2 is a cross-section at line 2 of Fig. 1. Fig. 3 is a detail, being a partial section at the same line as Fig. 2.

Fig. 4 is a section at line 4 of Fig. 1, the spring at one end of the pawl-bar I being omitted.

The objects of my invention are to provide an improved key-arrester; to provide improved devices for locking all of the keys, except those which are being operated; to provide devices, by means of which, when the keys which are not being operated have been locked and the drawer opened, such locked keys will remain locked until the drawer has been closed, and be unlocked by the closing of the drawer, all of which I accomplish, as illustrated in the drawings, and as hereinafter described.

That which I claim as new, and desire to secure by Letters Patent, will be pointed out in the claims.

In the drawings, A represents a metal frame, in which the working parts of the machine are supported, as usual.

B is a series of keys, pivoted on a shaft C, as usual.

D is the so-called "bell-bar," the ends of which are secured to arms a, which are pivoted on a shaft E, as usual.

F are levers, one for each key. The forward end of each lever is connected loosely with the rear end of one of the keys, and the rear end of each lever is pivoted on the shaft E. Each lever F is, as shown, provided with a projection b, arranged to engage with a bell-bar D.

G are springs, one for each lever F. On each key there is a plate H, which, as shown, is integral with the key.

c are teeth and notches on the upper edge of each plate. A portion d of the upper edge

of each plate, near the inner end thereof, is 50 not provided with notches, but is smooth.

e is a tooth at the end of each plate.

f is a smooth surface on the upper edge of each plate near the key.

I is a bar pivoted at its ends in the frame, 55 which bar serves the purpose of a pawl for all the keys, and may be called a "pawl-bar." The upper part g of this bar is flat. The lower side h of this bar is narrow, and is provided, as shown, with two angular edges i.j.

k are two springs arranged to act on the pawl-bar I. These springs hold the bar I in its normal position (shown in Fig. 2) when the keys are at either end of the stroke, and when a key is being pulled forward these springs 65 hold the edge i of the bar I in engagement with the notches c, as shown in Fig. 3, and when a key, having been operated, is returning to its normal position the springs hold the edge j of the bar I in engagement with the 70 notches c, as shown in Fig. 4.

J is another pawl-bar pivoted in the frame, which pawl-bar is arranged to engage with the teeth e on the several plates H.

l is a spring arranged to hold the pawl-bar 75 J out of engagement with the teeth e.

K is a short standard connected with the bell-bar D. The upper edge of this standard is flat and the front edge is curved.

L is a lever pivoted at m. One end of this 80 lever is arranged to engage with the top and front edge of the standard K, and the other end engages with the pawl-bar J.

M is a rod secured in the ends of the frame surrounded with rubber, which rod serves the 85 purpose of a stop when the keys return to their normal position after having been operated.

The operation of the parts of my invention already described is as follows: When the 90 keys are in their normal position, the pawl-bar I will be in the position represented in Fig. 2. If one of the keys be pulled forward, the teeth c will engage with the edge i on the pawl-bar I, causing it to assume the position 95 shown in Fig. 3, and then the springs k will have a tendency to hold such pawl-bar in that position which prevents the key from return-

ing or being returned to or toward its normal position until after it has completed its full stroke, at which time the lower part of the bar I will come to the smooth part *d* on 5 the plate II, and when the key returns to its normal position the teeth *e* will engage with the edge *j* of the pawl-bar I, which will come into the position shown in Fig. 4, and then the springs *k* will have a tendency to hold 10 such edge *j* in engagement with the teeth and notches *e*, which will prevent the key from being moved in the opposite direction until after it has completed the return movement. When either one of the keys B is pulled forward, the bell-bar D is immediately raised 15 through the operation of the proper lever F, which causes the front edge of the standard K to pass over the rear end of the lever L, lifting such end, and thereby depressing the 20 opposite end, which, being in contact with the pawl-bar J, forces such bar down into engagement with the teeth *e* on all of the keys which are not being operated, thereby locking 25 all of such keys.

25 I will now describe devices, by means of which the keys when locked, as above stated, are held locked until released by the closing of the drawer.

30 N is a money-drawer, which, as shown in Fig. 4, is supposed to be open. This drawer runs on rollers.

35 O is a rod secured to the rear end of the drawer, which rod passes between two rollers pivoted to the standard P. The devices for holding the drawer locked and for unlocking the same are not shown, being no part of this invention.

40 Q is a lever pivoted at its upper end to the frame. n is an arm which extends forward from the lower end of this lever Q, with the forward end of which arm the rear end of the drawer N comes in contact when it is closed. The upper end of the lever Q is cut away, so that there is a notch *p* in such lever.

45 q is an arm or bar secured to the bell-bar D, the forward end *r* of which arm is bent at right angles and engages with the front edge of the lever Q.

S is a spring arranged to act on the lever Q.

50 When one of the keys is operated, the bell-bar will be raised by the action of the proper lever F, which will carry the arm *q* upward until the part *r* of such arm passes into the notch *p* in the lever Q, the lever L being at 55 the same time operated upon, as before described, forcing the pawl-bar J into engagement with the teeth *e* on the plates II of the keys which are not being operated. So long as the arm or bar *q* remains in engagement 60 with the notch *p* the bell-bar will be held in its raised position, (indicated by dotted lines in Fig. 4,) which will hold the lever L in engagement with the pawl-bar J, in which position the locked keys cannot be operated.

The drawer N is supposed to have been opened at the proper time. When the drawer is closed, its rear end will engage with the forward end of the arm *n* on the lever Q, forcing the lever back and releasing the forward end *r* of the arm *q* from the notch *p*, when the bell-bar will return to its normal position, releasing the lever L and pawl-bar J, and then any of the keys which were locked can be operated.

75 What I claim as new, and desire to secure by Letters Patent, is as follows:

1. In a cash-register, a series of keys, each provided with a plate having a series of notches on one edge, in combination with a pivoted pawl-bar having two angular edges arranged to engage with the notches in the plates, for the purpose of preventing a key which is being operated from returning toward its normal position before it has completed its stroke, substantially as specified.

2. In a cash-register, a series of keys, each provided with a plate having a series of notches on one edge and parts *d* *f* without notches, in combination with a pivoted pawl-bar having two angular edges to alternately engage with the notches in the plates, substantially as and for the purpose specified.

3. In a cash-register, a series of keys, each provided with a plate having a series of notches on one edge and parts *d* *f* without notches, in combination with a pivoted pawl-bar having two angular edges to alternately engage with the notches in the plates, and springs to act on the pawl-bar, substantially as and for the purpose specified.

4. In a cash-register, a series of keys, each provided with a plate having a tooth *e* at its end, in combination with a pawl-bar J, arranged to engage with the several teeth *e* for locking the unoperated keys, substantially as and for the purpose specified.

5. In a cash-register, a series of keys, each provided with a plate having a tooth *e* at its end, a bell-bar D, and a series of levers F, one for each key, in combination with a standard K on the bell-bar, a pawl-bar J, and a lever L, substantially as and for the purpose specified.

6. In a cash-register, a series of keys, each provided with a plate having a series of notches on one edge and a tooth *e* at its end, and a pivoted pawl-bar arranged to engage with the notches in the plates, in combination with a pawl-bar J to engage the teeth *e*, a bell-bar D, levers F, standard K, and lever L, substantially as and for the purpose specified.

7. In a cash-register, a series of keys, each provided with a plate having at its end a tooth, a pawl-bar to engage the teeth *e*, levers F, a bell-bar D, carrying a standard K, a lever L, a drawer N, and intermediate devices between the drawer and lever L, substantially as described, for holding the pawl-

bar J in its locked position until released by the closing of the drawer, substantially as specified.

8. In a cash-register, the combination of a series of keys, each provided with a plate having at its end a tooth e, a series of levers F, a pawl-bar J, a bell-bar D, standard K,

lever L, lever Q, having an arm n and notch p, an arm or bar q, and drawer N, substantially as and for the purposes specified.

THOMAS CARNEY.
